CLAIM

The ornamental design for an implement used for supporting a chemical test kit in a swimming pool or the like, as shown and described.

DESCRIPTION

FIG. 1 is a side elevational view of an implement used for supporting a chemical test kit in a swimming pool or the like, showing our new design;

FIG. 2 is a top plan view thereof;

FIG. 3 is a bottom plan view thereof;

FIG. 4 is a left side and elevational view thereof, and;

FIG. 5 is a right side elevational view thereof.

FIG. 1.

FIG. 2.

FIG. 3.

FIG. 4.

FIG. 5.
